CENTRIFUGAL SWITCH

Earl R. O'Cathey, Pomona, Calif., assignor to Eror
Manufacturing Co., Pomona, Calif.

Application August 30, 1956, Serial No. 42,787

Term of patent 14 years

(Cl. D26—13)

Fig. 1 is an end elevational view of a centrifugal switch, showing my new design, the opposite end having substantially the same appearance;

Fig. 2 is a side elevational view, the opposite side having substantially the same appearance;

Fig. 3 is a bottom plan view; and

Fig. 4 is a top plan view thereof.

I claim:

The ornamental design for a centrifugal switch, substantially as shown.
